FIG. 1.

H. R. VAN DEVENTER.
IGNITION SYSTEM.
APPLICATION FILED DEC. 28, 1916.

1,229,351.

Patented June 12, 1917.
2 SHEETS—SHEET 2.

Inventor
Harry R. Van Deventer.

UNITED STATES PATENT OFFICE.

HARRY RANDOLPH VAN DEVENTER, OF SUMTER, SOUTH CAROLINA, ASSIGNOR TO SPLITDORF ELECTRICAL COMPANY, OF NEWARK, NEW JERSEY, A CORPORATION OF NEW JERSEY.

IGNITION SYSTEM.

1,229,351.

Specification of Letters Patent. Patented June 12, 1917.

Application filed December 28, 1916. Serial No. 139,322.

To all whom it may concern:

Be it known that I, HARRY R. VAN DEVENTER, a citizen of the United States, residing at Sumter, in the county of Sumter and 5 State of South Carolina, have invented certain new and useful Improvements in Ignition Systems, of which the following is a specification, reference being had to the accompanying drawing.

10 The invention relates to new and useful improvements in ignition systems, and more particularly to an ignition system in which make-and-break igniters are employed.

An object of the invention is to provide 15 an ignition system of the above character wherein the ignition current is generated by a magneto, and the opening of the contacts of the igniter is controlled by the ignition current generated by the magneto, so that 20 the time of breaking of the contacts is determined by the electrical action of the magneto, thereby eliminating all lag that frequently occurs when mechanical devices are relied upon to separate the contacts.

25 A further object of the invention is to provide an ignition system of the above character wherein the actuating mechanism for the magneto closes the igniter contacts, after which they are held in closed position by a 30 locking mechanism which is tripped by an electromagnet which is in turn controlled by the ignition current generated by the magneto.

A still further object of the invention is to 35 provide a supporting bracket for a make-and-break igniter and also for the magneto for generating an ignition current for the igniter wherein the contacts are closed by the actuating mechanism of the magneto, and 40 wherein said contacts are opened by mechanism controlled by the ignition current generated by the magneto, which magneto and actuating mechanism therefor is so constructed that the magneto may be removed 45 from the bracket without disturbing the train of devices which resets or brings the contacts into closed position.

These and other objects will in part be obvious and will in part be hereinafter more 50 fully disclosed.

In the drawings, which show by way of illustration one embodiment of the invention:-

Figure 1 is a front view showing an igniter system embodying the improvements;

Fig. 2 is a view, more or less diagrammatic and partly in section, showing the igniter, the controlling magnet, the locking mechanism for holding the contacts closed, and the actuating or resetting mechanism 60 for moving the contacts in closed position.

In carrying out the invention, I have provided an igniter of the make-and-break type which may be of any suitable construction. The contacts are normally held closed 65 through a suitable locking mechanism which is controlled by an electromagnet, and this electromagnet is in turn controlled by the ignition current so that, when the ignition current is at a maximum, the contacts may be 70 separated for producing the desired spark. The ignition current is supplied through a magneto, preferably of the type wherein the rotor or armature is oscillated for producing the desired ignition current. The armature 75 is oscillated through a push rod controlled by the engine, and coöperating springs which return the armature quickly to normal stationary position when released by the push rod. The tripping device actuates a spring 80 controlled lever which resets or brings the contacts into engagement. When the contacts are closed, they are locked in closed position, and they are afterward released by the electromagnet which is controlled by the 85 ignition current generated by the magneto.

Referring more in detail to the drawings:-

My improved ignition system includes a supporting bracket 1 which is secured in any 90 desired way to the wall of the cylinder, and mounted in this bracket is an igniter which includes a fixed electrode 2 carrying a contact or igniter point 3. Coöperating with this fixed electrode is a movable electrode 4 95 which extends through the wall of the cylinder and carries an arm 5 on which is mounted a contact or igniter point 6. On the other end of the electrode 4 there is an arm 7. A spring 8, secured at one end to said arm 7 100 and at its other end to a lug 9 carried by the supporting bracket 1, normally tends to turn the arm 7 so as to separate the contacts, and the movement of the arm is limited by a stop 10.

Removably mounted on the bracket 1 is a magneto 11 which consists of a permanent magnet 12 and an oscillating rotor or armature, the axis of which is indicated at 13. This armature or rotor is of the well- 110

known construction and has not been shown in detail. The armature or rotor is actuated by a trip lever 14 which is mounted so that its center is in line with the axis of the armature, although this trip lever is preferably disconnectible from the armature so that the magneto may be readily removed.

The trip lever is pivotally supported by the main bracket 1. Said trip lever has 10 oppositely extending arms 15 and 16, and the springs 17 and 18 are connected respectively to these oppositely projecting arms 15 and 16. The outer ends of the springs 17 and 18 are connected respectively to abutment pins 19 and 20. The trip lever is oscillated by a push rod 21 which is connected to some moving part of the engine. This push rod operates in the well-known way. When it is moved in the direction of the arrow in 20 Fig. 1, it engages the arm 22 of the trip lever, raises the same, and finally slips off of said arm, owing to the fact that the end of the arm moves in an arc of a circle, while the push rod moves in a straight line. When 25 the trip lever is released it causes the armature or rotor to have a quick movement to its normal stationary position, and this generates the ignition current. When the end of the arm 22 is raised by the push rod, the 30 arm 23 of the trip lever moves downwardly, as viewed in Fig. 1.

Mounted on the movable electrode is a setting lever 24. Said setting lever 24 partially surrounds the electrode but is formed 35 with a space between its ends indicated at 25 in the drawings. A spring 26 attached at one end to the lever 24 and at the other end to a pin 27 on the bracket normally tends to move the lever 24 in a clockwise direction about the center of the electrode 4. The shoulder 28 of the lever 24, when said lever moves in a clockwise direction, engages the under face of the arm 7 and raises said arm, thus moving the electrode so as to 40 carry the movable contact or ignition point into engagement with the fixed contact or ignition point. The spring 26 becomes effective to bring about this action when the end 23 of the trip lever moves downwardly, 45 as viewed in Fig. 1.

The arm 7 is locked in raised position with the contacts in engagement by a pivoted arm 29. This pivoted arm may be the armature or connected to the armature of 50 an electromagnet indicated diagrammatically in Fig. 2 of the drawings. The cores of the electromagnet are indicated at 30. A spring 31 is connected to this arm 29 and to the bracket and normally tends to move 55 the arm away from the cores of the electromagnet. The ignition current generated by the magneto is led through a line 32, first about the cores of the electromagnet and then to the stationary contact or ignition point. The movable contact or ignition

point is connected to the igniter frame so that the return circuit is through a ground. The coils of the electromagnet are wound in any well-known manner, and are so proportioned that, when the ignition current reaches a sufficient maximum so as to provide an efficient spark, then the electromagnet becomes effective to draw the armature 70 29 from underneath the arm 7 and the spring 8 at once moves the arm and separates the 75 contacts.

The operation of my device is thought to be clear from the above description. As the push rod moves in an upward direction for the purpose of setting the magneto, it will 80 at the same time release the lever 24 so that the spring 26 may move said lever to lift the arm 7 and bring the contacts into engagement. The arm 29 moving underneath the arm 7 holds the contacts in engagement so 85 that, when the trip lever is released by the push rod and the lever 24 is moved in a counter-clockwise direction through the action of the trip lever, the contacts will still be held in engagement. When the armature 90 is rotated through a sufficient distance to generate a maximum current for producing an efficient spark, the ignition current thus generated by the magneto will energize the electromagnet which will in turn move the 95 arm 29 from underneath the arm 7 and this permits the contacts to quickly separate, thus forming the spark.

From the above, it will be noted that the time of separating the contacts for ignition 100 is controlled by the electrical action of the magneto, and I have, therefore, been able to do away with any lag which frequently results when mechanical devices are used for separating the contacts. Any wear or looseness in the parts when the mechanical devices are used may result in the opening of the contacts either too early or too late for the maximum generated ignition current 105 which gives the ignition spark.

It will be noted that the igniter, the magneto, the actuating mechanism therefor, and the controlling devices for closing and separating the contacts are all carried by a single bracket, thus producing a unitary structure. 110 It will also be noted that the actuating mechanism for the magneto which also resets the igniter or moves the contacts into closed position is mounted independently 115 of the magneto on the bracket so that the magneto may be removed without disturbing this actuating mechanism which resets the igniter. It will also be noted that the trip lever is formed of one piece of metal, and this trip lever is adapted to engage an 120 adjustable set screw 33 carried by the lever 24.

It is obvious that minor changes in the details of construction and the arrangement of parts may be made without departing from 130

the spirit of the invention, as set forth in the appended claims.

Having thus described the invention, what is claimed as new is:—

5. 1. An ignition system including a make-and-break igniter, a magneto, actuating mechanism for the magneto, means for closing the igniter contacts, locking mechanism for holding the contacts closed, and electro-
10 magnetic means controlled by the ignition current generated by the magneto for releasing the locking mechanism to permit the contacts to open.
2. An ignition system including a make-and-break igniter, a magneto, actuating mechanism for the magneto, means operated by said actuating mechanism for closing the igniter contacts, locking mechanism for holding the contacts closed, and electro-
15 magnetic means controlled by the ignition current generated by the magneto for releasing the locking mechanism to permit the contacts to open.
3. An ignition system including a stationary igniter contact, a movable igniter contact, a spring for normally holding said contacts separated, a magneto for furnishing an ignition current to said igniter contacts, actuating mechanism for said magneto, de-
20 vices controlled by said actuating mechanism for moving said contacts into engagement, means for locking the contacts in engagement, and an electromagnet controlled by the ignition current generated by the
25 magneto for releasing the movable contact to permit the spring to open the contacts.
4. An ignition system including a station-
30 ary igniter contact, a movable igniter contact, a spring for normally holding said contacts separated, a lever, a spring for operating said lever, said lever being constructed and arranged so as to move the contacts into engagement, a magneto, a tripping device for said magneto, said tripping device co-
35 operating with said lever for moving the same against the action of the spring so as to permit the contacts to be separated, means for locking the contacts in closed position, and an electromagnet for releasing the contacts to permit the spring controlling the same to separate the contacts.
5. An ignition system including a station-
40 ary igniter contact, a movable electrode carrying a movable igniter contact, an arm projecting from said movable electrode, a spring connected to said arm for normally separating the contacts, a lever mounted on said electrode and having means for engaging the arm for moving the same in a direction to close the contact, a spring for mov-
45 ing said lever, said spring being of greater tension than the spring for separating the contacts, whereby said lever will close the contacts, a trip lever operated by the engine for moving said lever to permit the contacts to be separated, means for locking the contacts in engagement when closed, an elec-
50 tronmagnet controlled by the ignition current for releasing the movable electrode to permit its actuating spring to separate the contacts.
6. An ignition system including a station-
55 ary igniter contact, a movable electrode carrying a movable igniter contact, an arm projecting from said movable electrode, a spring connected to said arm for normally separating the contacts, a lever mounted on said electrode and having means for engaging the arm for moving the same in a direction to close the contact, a spring for mov-
60 ing said lever, said spring being of greater tension than the spring for separating the contacts, whereby said lever will close the contacts, a trip lever operated by the engine for moving said lever to permit the contacts to be separated, means for locking the contacts in engagement when closed, an elec-
65 tronmagnet controlled by the ignition current for releasing the movable electrode to permit its actuating spring to separate the contacts.

In testimony whereof I hereunto affix my signature.

HARRY RANDOLPH VAN DEVENTER.
